DISPENSING CARTONS PROVIDED WITH CUTTERS

James Edward Annen, Kalamazoo, Mich., assignor to Sutherland Paper Company, Kalamazoo, Mich., a corporation of Michigan

Application May 5, 1954, Serial No. 427,718

6 Claims. (Cl. 206—58)

This invention relates to dispensing cartons provided with cutters.

The main objects of this invention are:

First, to provide in a dispensing carton a cutter structure which constitutes an effective reinforcement and binding for the wall to which it is applied and acts to counteract the tendency of the wall to which it is applied to bow outwardly.

Second, to provide in a dispensing carton a cutter of downwardly facing section which embraces the edge of a wall of the carton and is effectively secured thereto to constitute a reinforcement and binding for the wall to which it is applied.

Objects relating to details and economies of the invention will appear from the description to follow. The invention is defined in the claims.

A preferred embodiment of the invention is illustrated in the accompanying drawing, in which:

Fig. 1 is a front perspective view of a dispensing carton embodying my invention with a portion of the web of paper withdrawn from the carton.

Fig. 2 is an enlarged fragmentary section on a line corresponding to line 2—2 of Fig. 1.

Fig. 3 is an enlarged front elevational view.

Fig. 4 is an enlarged inside elevational view of the front wall and cutter thereof.

Fig. 5 is a plan view of the carton.

It will be understood that no attempt has been made to show the parts in their relative proportions and in Fig. 2 the material of the carton, the material dispensed and the cutter are illustrated much thicker than the actual material used in the commercial structure.

Referring to the accompanying drawing, the carton designated generally by the numeral 1 is of the collapsible type but as the details of the collapsible features form no part of this invention they are not here illustrated or described.

The carton illustrated comprises a front wall 2 and cover 3 having a tucking flap adapted to be disposed at the inner side of the front wall. The paper 5, conventionally illustrated as being a transparent film or web, is commonly in a roll loosely positioned in the carton. The web of paper is passed under the flap 4 and upwardly between the flap and the front wall 2 as illustrated in Fig. 2.

The cutter designated by the numeral 6 is of downwardly facing channel or U-section, the bight portion 7 being upwardly curved. The lower edges of the arms 9 and 10 terminate in inturned flange-like portions 8 and 11. The arm 9 is substantially wider than the arm 10 so that both edges may be substantially embedded in the wall, even when it is of thin stock, to provide an effective grip thereon without materially severing or weakening the wall. The wall is clamped between the arms. The edge 111 of the arm 10 is desirably positioned opposite the angle or bend in the arm 9. The cutter is provided with teeth 12, desirably A-shaped, which are

2

struck out from the bight portion of the cutter. The teeth are spaced at their bases and merge into the arm 9 of the cutter. This provides bridge-like portions 13 between each adjacent pair of teeth connecting the arms 9 and 10 so that the cutter effectively resists stresses in all directions.

5 The tips of the teeth project above the bight of the cutter.

The cutter is substantially the length of the wall to which it is applied and is disposed over the edge thereof and clamped thereon, and constitutes an effective binding 10 and reinforcing member therefor. As shown in Fig. 4, the cutter is longitudinally curved inwardly and the central portion thereof is desirably in springable thrust engagement with the material disposed between the cutter and the closure flap as shown in Fig. 2. This acts to 15 retain the end of the dispensable material in position for grasping and also the inward bowing of the cutter counteracts the outward pull on the material as the material is drawn over the cutter preparatory to severing and while being severed.

20 Thus formed and arranged the cutter, even when formed of quite light sheet metal stock as is the commercial practice, serves as an effective binding and reinforcement for the wall of the carton to which the cutter is applied and which is subjected to stress in dispensing the material.

25 I have illustrated the invention in an embodiment which has been found very practical. I have not attempted to illustrate or describe other adaptations which I contemplate as it is believed this disclosure will enable the practice of the invention as may be desired.

30 Having thus described the invention what is claimed as new and desired to secure by Letters Patent is:

1. A dispensing carton including a front wall and cover therefor having a closure flap adapted to be positioned on the inner side of the front wall, a cutter of 35 downwardly facing U-shape having a bight portion and substantially parallel arms terminating in inwardly converging flange-like edge portions, a series of teeth struck out from the bight portion with their bases spaced and merging into one arm of the cutter with their tips projecting above the bight thereof, the portions of said bight portion intermediate the spaced bases of the teeth integrally connecting the parallel arms of the cutter to each other, said cutter being of a length substantially that of the front wall and being embracingly disposed over the 40 edge of the front wall with the arms thereof in fixedly clamped engagement therewith, and with the flange-like edge portions of the arms in embedded engagement with the front wall, said cutter constituting a reinforcing and binding element for the edge of the front wall and having the portion thereof intermediate the ends of the cutter bowed longitudinally of the cutter and inwardly relative to the carton and towards the closure flap disposed on the inner side of the front wall whereby the central portion 45 of the cutter is normally in springable thrust engagement with the dispensed material between it and the closure flap and whereby the cutter counteracts outward bending of the central portions of the cutter and front wall when the dispensed material is pulled out of the carton and over the cutter preparatory to and while severing the material.

2. A dispensing carton including a front wall, a cutter of downwardly facing U-shape having a bight portion and substantially parallel arms terminating in inwardly converging flange-like portions, and a series of teeth struck 55 out from the bight portion with their bases spaced and merging into one arm of the cutter with their tips projecting above the bight thereof, the portions of said bight portion intermediate the spaced bases of the teeth integrally connecting the parallel arms of the cutter to each other, said cutter being of a length substantially that of the front wall and being embracingly disposed

over the edge of the front wall with the arms thereof in fixedly clamped engagement therewith and said cutter constituting a reinforcing and binding element for the edge of the front wall and having the central portion thereof bowed longitudinally of the cutter and inwardly relative to the carton whereby the cutter counteracts outward bending of the central portions of the cutter and front wall when the dispensed material is pulled outwardly of the carton and over the cutter preparatory to and while severing the material.

3. A dispensing carton including a wall, and a cutter of downwardly facing channel section embracingly disposed over the edge of the wall and having a series of integral teeth struck out from and projecting above the bight portion thereof, the bases of the teeth being spaced, the arms of the cutter being integrally connected by bight portions between each adjacent pair of teeth, said cutter being of a length corresponding to the length of the wall and being normally curved longitudinally of the cutter and inwardly relative to the carton and being disposed over the edge thereof with its arms retainingly clamped thereon whereby the cutter is secured to the wall and constitutes a reinforcement binding for the edge thereof and supporting the edge normally in an inwardly curved position.

4. A dispensing carton including a wall, a cutter of downwardly facing channel section having a bight portion and substantially parallel arms connected thereby, and a series of teeth disposed adjacent the bight portion, said cutter being disposed over the edge of the carton

wall with its arms retainingly clamped thereon whereby the cutter is secured to the wall and constitutes a reinforcement and binding for the edge thereof, said cutter being curved longitudinally thereof and inwardly relative to the carton and normally supporting the edges of the wall in inwardly curved position.

5. A cutter for a dispensing carton, said cutter being of channel section and having a bight portion and opposed arms for clampingly embracing an edge portion of a carton, and a series of spaced teeth struck from the bight portion, the portions of the bight portion intermediate the bases of teeth integrally connecting the arms to each other, said cutter being bowed longitudinally thereof.

6. A cutter for a dispensing carton, said cutter being of channel section and having a bight portion and opposed arms for clampingly embracing an edge portion of a carton, and a series of teeth disposed adjacent the bight portion, said arms terminating in flange-like edge portions converging towards each other for embeddingly engaging the edge portion of a carton, the width of one of said arms substantially exceeding that of the other arm.
